UNITED STATES PATENT OFFICE.

JOHN S. BARNES, OF ANN ARBOR, MICHIGAN, ASSIGNOR TO WIRE PRODUCTS CORPORATION, OF ANN ARBOR, MICHIGAN, A CORPORATION OF MICHIGAN.

WIRE FABRIC.

Application filed December 14, 1921. Serial No. 522,213.

To all whom it may concern:

Be it known that I, JOHN S. BARNES, a citizen of the United States, residing at Ann Arbor, county of Washtenaw, State of Michigan, have invented a certain new and useful Improvement in Wire Fabrics; and declare the following to be a full, clear, and exact description of the same, such as will enable others skilled in the art to 10 which it pertains to make and use the same, reference being had to the accompanying drawings, which form a part of this specification.

My invention relates to a wire fabric shown in the accompanying drawings and more particularly described in the following specification and claims. The wire fabric shown is especially adapted for partitions, window guards, crates, tops for 20 commercial vehicles, waste paper burners, etc.

Heretofore it has been found necessary in the use of a wire fabric of this character to secure the marginal edges of the fabric within an enclosing frame or to another 25 member to insure rigidity of construction: it being apparent that unless the ends of the respective warp and woof wires are secured together the several members are apt to become displaced due to their tendency to turn upon the points of intersection between the wires.

One of the objects of this invention therefore is to provide a fabric designed to overcome this objection without the employment of an enclosing frame or the attachment of the fabric to some rigid member to secure the respective members of the 35 fabric in fixed relation. In putting this invention into effect the wire strand forming the warp of the fabric is continuous and is bent back and forth at the ends to provide a plurality of parallel return bends, in spaced relation to each other, the return bends being arbitrarily spaced in 40 conformity to the predetermined mesh of the fabric. Intersecting the continuous warp member are a plurality of woof members also spaced apart, their ends being secured to the outer or marginal bends of 45 the warp member by looping the woof members preferably around the latter.

A further object of the invention is to provide a fabric of indefinite length in the form of panels for use in constructing

partitions or other like work, the fabric being thus readily adapted however for shipment;—to this end the panels are connected together by intermediate metallic strips engaging the alternately looped ends connecting the return bends of the warp 60 of the fabric.

A further object of the invention is to provide for securing these intermediate metallic strips to suitable supporting members, as for example the usual framing of 65 a building or like support.

A further object is to provide means whereby any one or several panels may be adapted to swing with reference to the connecting panel that it may serve as a door. 70 If desired however the fabric may be supported in an enclosing frame in which suitable hinges or locking mechanism may be installed.

The invention further resides in the combination and arrangement of parts and in the details of construction hereinafter described and claimed, it being understood that changes may be made in the precise embodiment of the invention herein disclosed without departing from the spirit 75 of the same.

In the drawings accompanying this specification:

Figure 1 is a fragmentary perspective 85 view of the fabric employed as a partition,—a portion of two panels being shown, joined together by connecting metallic strips;—one of the panels serving as a gate secured in closed position by a suitable 90 lock;

Fig. 2 is a front elevation of two panels of the fabric joined together by a connecting metallic strip adapted for engagement with the studding of a building; 95

Fig. 3 is a perspective view of a basement window showing the fabric in use as a window guard with means for locking it in closed position; and

Fig. 4 is a cross-sectional view through 100 the frame of the basement window showing in dotted lines the guard in its open position.

Referring now to the letters of reference placed upon the drawings:

A denotes a continuous strand of plain or crimped wire forming the warp of the fabric,—the fabric being preferably con-

structed in suitable panels of arbitrary width and length, the strand forming the warp being bent at substantially right angles alternately at each side or end of the fabric 5 to provide for a return bend A', in predetermined spaced relation to the adjacent parallel portion of the warp. Intersecting the return bends of the warp are a plurality of plain or crimped woof wires B, arranged 10 in parallel spaced relation to each other, their ends B' being bent to encircle the marginal return bends of the warp, to secure them to the latter. It will now be readily seen that a fabric so constructed will be 15 rigid due to the fact that the warp is continuous and the woof strands are securely connected with the outer marginal return bends of the warp. Panels of predetermined size may be joined together by transverse 20 sheet metal strips C, notched to form ears C', bent to encircle the looped ends or end bends A² connecting the return bends of the warp and having the ears staggered, as shown in Fig. 2, to engage alternately opposite looped ends A². D denotes apertures in the strip to receive nails or screws for securing the fabric to a suitable framing. The metallic strips may also be slotted as indicated at E, for the passage of a staple F, 25 fitted with a padlock G, if it is desired to employ one of the panels as a door. In Figs. 3 and 4 a panel is shown adapted for a basement window guard, and when so employed one of the metallic strips is secured 30 to the upper member of the window casing upon the inside of the guard, the lower strip being adapted to receive a staple H, for securing the guard when closed.

Having thus described my invention what 40 I claim is:

1. In a panel of wire fabric, a continuously crimped strand of wire forming the warp of the fabric looped alternately at each side of the panel to provide a plurality of 45 return bends spaced apart in substantially the same plane, a plurality of strands of crimped wire spaced apart intersecting the return bends of the continuous warp strand to form the woof of the fabric, the ends of 50 said woof wires being wrapped around the marginal bends of the warp wire to secure rigidity, and a metallic member adapted to connect the looped ends of the return bends of the continuous warp strand of one panel 55 with the looped ends of the continuous warp strand of an adjacent panel, said metallic

strip being adapted to be secured to a supporting frame.

2. In a panel of wire fabric, a continuously crimped strand of wire forming the warp of the fabric looped alternately at each side of the panel to provide for a plurality of return bends spaced apart in substantially the same plane, a plurality of strands of crimped wire spaced apart intersecting the 60 return bends of the continuous warp strand to form the woof of the fabric, the ends of said woof wires being secured to the marginal return bends of the warp wire, and a metallic member having ears adapted to encircle the looped ends of the return bends of the warp wire, said metallic member being slotted for the passage of a staple, whereby the panel may be secured to a supporting 70 frame.

3. In a panel of wire fabric, a continuous warp strand bent to form return bends at opposite edges of the panel, a plurality of woof strands interlaced therewith and having the ends thereof secured to the marginal return bends of the fabric, a metallic strip having spaced ears struck therefrom to engage the end bends of the fabric, and means for supporting the said strip.

4. In a panel of wire fabric, comprising a continuous warp strand bent to form return bends, a plurality of woof strands having the ends thereof secured to the marginal return bends of the fabric, a metal strip having spaced ears struck therefrom adapted to encircle the end bends of the fabric to form a pivotal connection, and means for supporting the said metal strip.

5. In a panel of wire fabric comprising a continuous warp strand bent to form return bends, a plurality of woof strands interlaced therewith and having the ends thereof secured to the marginal return bends of the fabric, a plurality of metal strips having ears struck therefrom adapted to secure the end bends of the fabric, the ears on the said strips being formed in staggered relation to each other to engage the opposite end bends, means for supporting the strips, and means for locking one of the said strips to a supporting frame.

In testimony whereof, I sign this specification in the presence of two witnesses.

JOHN S. BARNES.

Witnesses:

S. E. THOMAS,
IDA GOREN.
